UNITED STATES PATENT OFFICE.

GEORGE FREDERICK COGGESHALL BURKE, OF FAIRHAVEN, MASSACHUSETTS.

DESIGN FOR A SMOKING STAND.

Application filed November 14, 1923. Serial No. 7,760. Term of patent 7 years.

To all whom it may concern:

Be it known that I, GEORGE F. C. BURKE, a citizen of the United States, residing at Fairhaven, in the county of Bristol and State of Massachusetts, have invented a new, original, and ornamental Design for Smoking Stands, of which the following is a specification, reference being had to the accompanying drawing, forming part thereof.

Fig. 1 is a top plan view, and

Fig. 2 is a side elevation of a smoking stand showing my new design.

I claim:

The ornamental design for a smoking stand, as shown.

GEORGE FREDERICK COGGESHALL BURKE.
